UNITED STATES PATENT OFFICE.

EVERETT D. MOORE, OF BALTIMORE, MARYLAND, ASSIGNOR OF ONE-HALF
TO RUFUS W. APPLEGARTH, OF SAME PLACE.

WATER COIL BOILER.

SPECIFICATION forming part of Letters Patent No. 409,056, dated August 13, 1889.

Application filed May 8, 1889. Serial No. 310,000. (No model.)

To all whom it may concern:

Be it known that I, EVERETT D. MOORE, a citizen of the United States, residing at Baltimore, in the State of Maryland, have invented new and useful Improvements in Water Coil Boilers, of which the following is a specification.

The object of my invention is to provide an effective and convenient means for steaming, flushing, and thoroughly cleansing the pipes that are frequently employed for conducting beer, wines, and other liquids from a keg, barrel, or other source to the tap or faucet of a beverage-drawing apparatus, which pipes are liable to become fouled and internally coated with sediment from the liquors or beverages passed through them, especially when standing therein over night. The impurities that are thus deposited in the pipes of a beverage-drawing apparatus are liable to taint the liquor and are often injurious to health.

Heretofore the pipes of a beverage-drawing apparatus have been cleansed to some extent by forcing through them solutions of potash, lime, and other substances, which, however, are liable themselves to form injurious compounds in the pipes. My invention obviates these difficulties by providing a means for thoroughly cleansing the pipes with steam and hot water, as hereinafter described.

In the annexed drawings, illustrating the invention, Figure 1 is an elevation of my improved pipe steaming and cleansing apparatus. Fig. 2 is an enlarged plan of the steam-generator with its cover removed. Fig. 3 is an enlarged sectional elevation of the steam-generator and steam-separating chamber or manifold, with attached gages and relief-valve.

The steam-generator comprises a cylindrical metallic shell 1, resting on a flanged bottom plate 2, having legs 3, by which the generator is supported at a suitable height. On the upper end of the cylindrical shell 1 is placed a removable cover 4, which is preferably formed as the frustum of a cone, and is provided at the apex with a cylindrical chimney 5 for the escaping products of combustion.

In the lower part of the shell 1 is supported a horizontal gas-pipe 6, the inner end of which

is turned upward, as shown at 7 in Fig. 3, while its outer end projects beyond the shell for attachment of a piece of flexible tubing 8, that may be connected when desired with any convenient gas-supply pipe. On the inner end of the pipe 6 is supported any suitable gas-burner.

In Fig. 3 I have shown a construction that embodies the advantages of the Bunsen and Argand burners; but I would have it understood that I do not confine myself to a burner of any particular form of construction.

As shown in Fig. 3, the upturned inner end 7 of the gas-pipe 6 is surrounded by a vertical gas and air mixing tube 9, that is open at its lower end and closed at the top. A number of horizontal tubes 10 radiate from the upper portion of the gas and air mixing tube 9 and support an annular burner 11, having a series of perforations 12 for the exit of gas. These gas-exits are preferably arranged on the outer and upper portion of the annular burner tube 11, as shown, so as to direct the flames outward.

On the upper closed end of the gas and air mixing tube 9 is secured a deflector-plate 13, that is of greater diameter than the annular burner, so as to project somewhat beyond the same. The edge of this deflector is curved upward and outward, as shown, to direct the jet-flames of the annular burner against or toward the lower portion of a spirally-coiled water-pipe 14, that is supported within the generator-shell.

The coil 14 extends vertically through the greater part of the height of the generator-shell and is preferably in the form of the frustum of a cone, having its smaller diameter at the top or upper leg of the coil, where it receives water through an elbow 15, that connects with a horizontally-arranged pipe 16, Fig. 2, having a check-valve 17 and a hand-valve 18 located therein, the check-valve being arranged in that part of the pipe 16 which is within the shell 1, while the hand-valve 18 is near the outer end of the pipe 16 and exterior to the generator-shell, where it will be readily accessible. The outer end of the pipe 16 is preferably screw-threaded, as shown, for attachment of a flexible tube 19, Fig. 1, that

may connect with a faucet 20 on a stationary or fixed house-service pipe 21, that connects with a city water-main or other suitable supply having a sufficient head. The lower leg 5 of the coil 14 communicates through a pipe or tube 22 with the lower part of a drum or manifold 23, that serves as an expansion-chamber for the steam generated in the coil 14, and in which chamber or manifold the 10 steam and water are separated.

From the upper end of the chamber or manifold 23 the steam passes, through pipes 24, 25, and 26, connected by elbows 27, into the upper leg of a steam-superheating pipe 15 coil 28, that closely surrounds the upper portion of the steam-generating coil 14, and is preferably extended downward to near its lower end, leaving, however, sufficient space for the circulation of heated air between the 20 coils and the generator-shell. The lower leg of the steam-generating coil 28 is bent upward and extended to the top of said coil in the form of a vertical pipe 29, as shown by dotted lines in Fig. 3, to connect with horizontal 25 pipes 30 and 32 through elbows 31, Fig. 2, the pipe 32 being extended through the upper part of the generator-shell and provided on the outside thereof with a hand-valve 33 and with a threaded end for attachment of a hose 30 or flexible tube 34, through which water and steam can be conveyed to the pipes to be cleansed. In order to facilitate attachment of the hose 34, it may be provided with couplings 35, of ordinary construction.

35 For the purpose of obstructing the direct ascent of heat from the burner centrally through the coils to the chimney 5 a baffle-plate or deflector 36 is supported in any suitable manner in the lower part of the space in 40 closed by the inner or steam-generating coil 14 in such a manner as to deflect the heat outward into more direct contact with the steam generating and superheating coils, and thus cause the greater part of the products of combustion to circulate freely in the space between the coils and the generator-shell before escaping through the chimney.

It will be seen that the coils 14 and 28, one surrounding the other, afford within a compact space an extended heating-surface for generating and superheating steam, which surface is further extended by the manner of effecting communication between these separate coils through the drum or manifold 23, in 55 which the steam is allowed to expand before passing to the superheater.

A sufficient supply of air to support combustion and to provide for a proper mixture of gas and air in the burner is afforded through 60 air-inlets 37 in the lower part of the generator-shell.

In order to retain the heat of the apparatus as much as possible, the generator-shell 1 and the conical portion of the cover 4 are each 65 provided with a lining 38, of asbestos or other suitable material. For a similar purpose a piece of asbestos 39 is attached to the under

side of a metallic baffle-plate 40, that is supported horizontally above the coils 14 and 28 in the upper part of the generator-shell, so as 70 to cut off the direct upward passage of heat through the space surrounded by the steam generating and superheating coils. It will thus be seen that the heat is confined around and in proximity to these coils as long as possible, with the result of producing the most economical results in the heating of water and the generation and superheating of steam for the purposes to which the apparatus is to be applied. 80

The drum or expansion-chamber 23 is provided with a detachable bottom plate 41, that can be removed to draw off the water in said chamber and to facilitate cleansing the chambers when required. The chamber 23 is provided also with a detachable top plate 42, that can be removed for cleansing said chamber. In this top plate 42 is supported a relief-valve 43, the stem of which is provided with a spring 44, having a bearing at its upper end on a 85 cross-head 45, engaged with guide-rods 46, that are threaded for attachment of nuts 47, by which the valve can be adjusted to any required pressure.

A pressure-gage 48 is connected with the 90 expansion-chamber 23 by means of a pipe 49, that communicates with the upper part of said chamber. The expansion-chamber or drum 23 is provided also with a water-gage 50, of any suitable construction. Either the 95 relief-valve or the steam-pressure gage may be dispensed with, if desired. Should the relief-valve 43 be omitted, the hand-valve 33 can be used for blowing off steam, while by employing the relief-valve and setting it at 100 the desired pressure the gage 48 may be omitted.

In using this apparatus for cleansing pipes through which beer, wines, and other liquids have been conveyed from a keg or barrel to 110 the draft-tap or faucet of a beverage-drawing apparatus I prefer to first heat the coils 14 and 28 and the surrounding shell 1 by means of the atmospheric-gas burner in the lower part of said shell. The hand-valve 33 115 being closed and the hand-valve 18 partly opened, I admit water gradually into the coil 14 through the pipes 16 and 19, that connect with the faucet 20, as before described. For the purpose of generating steam in the coil 120 14 it is desirable that only a quantity of water sufficient to partly fill said coil should be supplied thereto, thus facilitating the generation and disengagement of steam in said coil.

After circulating slowly and in a comparatively small volume through the coil 14, the water and steam pass into the expansion-chamber 23, where the steam is wholly disengaged and then passes through the pipes 125 24, 25, and 26 into the superheating steam-coil 28, while more water is admitted to the steam-generating coil. The quantity of water and the pressure of steam in the apparatus will be indicated by the water-gage and 130

steam-pressure gage, respectively. When a sufficient quantity of superheated steam has been accumulated in the apparatus and the hose or flexible tube 34 has been attached 5 to the pipe to be cleansed, which pipe has been previously disconnected from the keg or barrel, the hand-valve 33 will be opened and a quantity of steam allowed to pass from the superheating-coil 28 into and through the 10 fouled pipe, whence it escapes at the tap or drawing-off faucet. The superheated steam thus conveyed into and through the pipe or pipes to be cleansed will soften, disintegrate, and detach the slime, scale, and sediment 15 that have been deposited in said pipe or pipes and will remove quantities of the same through the top or faucet at the exit end of said pipe. This sediment or scum in the fouled pipes being thus softened, the hand-valve 18 of 20 the steam-generator will be fully opened, so as to give the coil 14 a full supply of water, which quickly becomes heated, and passing through the chamber 23, coil 28, and hose 34 into the pipe to be cleansed removes therefrom 25 the loosened and detached scale or sediment. The supply of gas into the burner 11 can now be cut off and a continuous stream of cold water passed through the apparatus and the connected beer or wine conveying pipe to 30 cool the same and remove every vestige of sediment.

While the apparatus is in use for heating water and producing superheated steam, the hand-valve 33 being closed and the hand-valve 18 partly open, the check-valve 17 will prevent the regurgitation of hot water and steam and cause a steady circulation through the coils. By making the shell 1 detachable from the flanged bottom plate 2 and the cover 40 4 detachable from the shell, as shown, the steam-generator can be easily taken apart for cleansing, repairs, or transportation. The coil 14 may be supported on brackets 51, arranged in the lower part of the generator-shell.

45 For convenience in supplying the steam-generating coil 14 with the proper quantity of water to generate steam, which supply should not be sufficient to flood the coil, I prefer to provide on the water-inlet pipe 16 a by-pass tube 52, one end of which connects with the pipe 16 between the hand-valve 18 and the flexible tube 19, while the other end connects with the pipe 16 between the check-valve 17 and the steam-generating coil. In 50 this by-pass tube 52 is a petty valve 53, which is to be opened for supplying the coil 14 with just sufficient water to generate steam, the hand-valve 18 being meanwhile closed. After steam has been generated, superheated, and 55 delivered to the pipes of the beverage-drawing apparatus, as before described, the hand-valve 18 may be opened to flood the coil 14 and enable a sufficient quantity of water to be heated for the purpose of thoroughly flushing the pipes of the beverage-drawing apparatus with hot water. It is obvious that by 60 this arrangement of valves 18 and 53 the ap-

paratus can be successfully managed without requiring the services of a skilled engineer. If desired, the check-valve 17 may be omitted. 70

This apparatus will be found to be of great convenience and usefulness in cleansing pipes and tubing from the sediment of beer, wine, and other liquids, and as it does not require the use of lime, potash, or other chemicals to 75 soften and remove the scale it provides a means for thoroughly cleansing the pipes without the deleterious consequences to health that frequently result from the formation of injurious chemical compounds in such 80 pipes during the process of cleansing.

What I claim as my invention is—

1. The combination of a steam-generator comprising an outer shell having air-inlets near the bottom, a gas-burner located in the 85 lower part of said shell, a steam-generating coil supported above the burner, a steam-superheating coil surrounding the steam-generating coil, a drum or expansion-chamber located outside the generator-shell and communicating with the generating and superheating coils, a valved pipe for conveying water into the steam-generating coil, and a valved pipe leading from the superheating-coil, substantially as described. 95

2. The combination of a steam-generator comprising generating and superheating coils inclosed by a shell, a drum or expansion-chamber located outside the generator-shell in communication with said coils and provided with 100 water and steam gages, a pipe for supplying the steam-generating coil with water, a pipe for conducting steam and water from the superheating-coil through a hose to the pipe or pipes to be cleansed, and valves for controlling the inlet and outlet pipes of the generator, substantially as described. 105

3. The combination of a steam-generator comprising an outer shell having air-inlets and a chimney, a gas-burner located in the 110 lower part of the generator-shell, a steam-generating coil located above the gas-burner, a steam - superheating coil surrounding the steam-generating coil, a deflector-plate located above the burner in the lower part of 115 the space inclosed by the steam-generating coil, a baffle-plate located above said deflector, a heat - retaining plate located above the superheating and generating coils, and an asbestos lining for the generator-shell, substantially as described. 120

4. The combination of a steam-generator having steam generating and superheating coils, baffle-plates for retaining the heat in contact with said coils, a drum or expansion-chamber communicating with the generating and superheating coils, a valved pipe for delivering a regulated supply of water to the generating - coil, and pipes for conducting steam and water from the coils to the pipe or 130 pipes to be cleansed, substantially as described.

5. The combination, with a steam-generating coil 14, having inlet-pipe 16, provided with

valve 18, of the by-pass tube 52, provided with valve 53, substantially as described.

6. The combination of a heater, a pipe-coil located above the heater, a valved pipe leading into one end of the pipe-coil and having a valved by-pass also leading into said coil, and a flexible tube communicating with the coil and adapted to be connected to the pipe or pipes to be cleansed, substantially as described.

7. The combination of a water-heating and steam-generating coil having a valved inlet

provided with a valved by-pass, flexible tubing for delivering water to the said coil, and flexible tubing for conveying steam and water from the coil to the pipe to be cleansed, substantially as described.

In testimony whereof I have affixed my signature in presence of two witnesses.

EVERETT D. MOORE.
